PNEUMATIC HOIST

Walter Blair, Detroit, Mich.

Application January 10, 1950, Serial No. 137,785

1 Claim. (Cl. 60—57)

1
This invention relates to hoists, and in particular, to pneumatic hoists.

One object of this invention is to provide a pneumatic hoist having a normal sustaining pressure on one side of a piston capable of raising a given load, and means for applying an overbalancing pressure on the other side of the piston for forcing the load downward, thereby requiring the application of only a slight pressure to overbalance the load in order to lower it, and economizing on the amount of compressed gas required to be produced during operation.

Another object is to provide a pneumatic hoist of the foregoing character wherein the sustaining pressure is supplied from one compressed air tank having a pressure maintained at a predetermined amount sufficient to sustain the piston and its load in their raised positions, the overbalancing pressure for the opposite side of the piston being provided by a compressed air source at a different pressure, such as a second tank maintained at a different predetermined pressure either with or without a regulating valve.

Another object is to provide a pneumatic hoist of the foregoing character wherein the load is sustained in its raised position by air pressure from different sources at different pressures beneath different pistons in different cylinders connected to a common cross head or other structure to which the load is connected, the pressure and piston area in one cylinder being such that it is slightly less than that necessary to sustain the load, with the result that when pressure is released from the other cylinder, the remaining pressure in the first-mentioned cylinder is insufficient to sustain the load, which thereupon descends.

Another object is to provide a pneumatic hoist of the foregoing character wherein the sustaining air is returned to its particular tank when the load is caused to descend, either by applying an overbalancing pressure to the opposite side of the load-sustaining piston, or by removing the make-up pressure from a separate cylinder, this make-up pressure being ordinarily the slight amount necessary to add to the pressure in the other cylinder in order to sustain the load.

Another object is to provide a pneumatic hoist of the foregoing character which is especially well adapted to the raising and lowering of bowling pin pickups or setters for bowling pin-setting machines, and which employs tanks for compressed air or other gas which are adequate to serve a number of such machines.

In the drawing:

2

Figure 1 is a diagrammatic side elevation, partly in central vertical section, showing a pneumatic hoist, according to one form of the invention; and

5 5 Figure 2 is a side elevation, partly in central vertical section, of a modified pneumatic hoist, according to another form of the invention.

Referring to the drawing in detail, Figure 1 shows diagrammatically a pneumatic hoist, generally designated 10, adapted to raise and lower a load 11, such as a bowling pin pickup or setter for a bowling pin-setting machine. It is obvious, however, that other types of loads may be raised and lowered in a similar way by the same apparatus. Connected to the load 11 is the lower end of a piston rod 12 having a piston head 13 on its upper end, these together constituting the piston 14. The piston 14 is reciprocable in a bore 15 of a pneumatic cylinder 16 having upper and lower ports 17 and 18 connected respectively to pipes 19 and 20. The pipe 20 leads directly to a load sustaining pressure tank 21 to which compressed air or other suitable compressed gas is supplied through pipes 22 and 23 from a pressure supply tank 24 by way of a conventional pressure-regulating valve 25. It will be obvious that to avoid the setting up of an appreciable back pressure as the piston 14 is forced downward, the volume of the tank 21 must be large in proportion to the volume of the cylinder 16.

10 30 The pressure supply tank 24 is supplied with compressed air or other compressed gas through a supply pipe 26 containing a check valve 27 opening toward the tank 24 and connected to the outlet port of an air or other gas compressor 28 having an inlet pipe 29. The compressor 28 is driven by a shaft 30 connected to the armature shaft 31 of an electric motor 32, this assembly being bolted or otherwise secured to a base 33. The motor 32 is supplied with electric current

15 40 from wires 34 and 35 by way of a pressure-responsive switch, generally designated 36. The pressure-responsive switch 36 is conventional and its details are beyond the scope of the present invention. It is sufficient for purposes of the present invention to state that the switch 36 consists of a casing 37 connected by a pipe 38 to the pressure supply tank 24 and having a diaphragm 39 connected to a spring-pressed plunger 40, the latter in turn being connected to the switch

20 45 plunger 41 of the switch unit 42. When the pressure within the casing 37 rises beyond the point sufficient to overcome the counterbalancing spring of the plunger 40, the latter rises, pushes **25** 50 the switch plunger 41 upward, opens the switch

unit 42, de-energizes the motor 32 and halts the compressor 28. No further pressure is delivered until the pressure falls within the tank 24 sufficiently to permit the diaphragm 39 and plunger 40 to descend, closing the switch unit 42 and re-energizing the motor 32.

Compressed air or other gas from the pressure supply tank 24 passes through a pipe 43 and a conventional pressure-regulating valve 44 into a pipe 45, thence through an electro-magnetic valve 46 into the pipe 19 connected to the upper port 17 of the pneumatic cylinder 16. The pressure-regulating valves 25 and 44 are similar to one another but are set to pass different pressures, as explained in connection with the operation of the invention. The electro-magnetic valve 46 has an air discharge or vent pipe 47 which is open to the atmosphere when the wires 48 and 49 are supplied with electric current to energize the solenoid 50 so as to shift the valve plunger (not shown) of the valve 46, and release air from the space above the piston head 13 through the pipe 19 and valve 46 into the discharge pipe 47, and thence to the atmosphere.

In the operation of the form of the invention shown in Figure 1, the pressure-regulating valve 25 is set at a pressure sufficient, when applied against the underside of the piston head 13, to raise the load 11 and sustain it in its raised position, for example at 75 pounds per square inch. The pressure-regulating valve 44, on the other hand, is set to pass gas at pressures below another predetermined pressure sufficient to overbalance the pressure in the cylinder 16 beneath the piston head 13 and lower the load 11, for example, 15 pounds per square inch. The pressure-responsive switch 36, on the other hand, is set at a sufficient pressure to maintain an adequate pressure in the pressure supply tank 24 for the foregoing purposes, for example, 90 pounds per square inch. Thus, the compressor 28 is driven by the motor 32 to supply compressed air or other gas to the tank 24 so long as the pressure therein is insufficient to raise the diaphragm 39 and plunger 40 to open the switch unit 41 of the pressure-responsive switch 36 and halt the motor 32.

Thus, under normal conditions with the load 11 raised, the pressure above the piston head 13 has been released by opening the valve 46 and discharging the compressed air therein through the vent pipe 47. When however, it is desired to lower the load 11, the electro-magnetic valve 46 is shifted so as to close off the vent pipe 47 and pass compressed air from the pipe 45 to the pipe 19 and thence through the port 17 into the space above the piston head 13. This pressure, although at a much lower pressure in pounds per square inch than the pressure existing below the piston head 13 is nevertheless sufficient to overbalance the sustaining pressure and, aided by the weight or force of the load 11, to cause the load to descend. In this manner, for example, the pins in the bowling pin setter may be lowered to the alley and thereby set up on the alley.

Thus, even though only a slight overbalancing pressure is required to be exerted above the piston head 13, only the air required for this overbalancing pressure is subsequently lost by being vented through the pipe 47 when the load is again raised, because the sustaining compressed air beneath the piston head 13 is forced out of the cylinder 16 through the port 18 and pipe 20 back into the load-sustaining pressure tank 21 when the piston 14 and load 11 descend. The com-

pressed air in the load-sustaining pressure tank 21 is thus used over and over.

The modified pneumatic hoist, generally designated 60 shown in Figure 2 is for the same purpose as that shown in Figure 1, except that two single acting cylinders are employed rather than a single double-acting cylinder. The pressure supply tank 61, like the pressure supply tank 24 of Figure 1, is similarly supplied with compressed air or other gas by a similar compressor 28 driven by a similar motor 32 and regulated by a similar pressure-responsive switch 36 in the manner described in connection with Figure 1, similar parts bearing the same reference numeral. Pipes 62 and 63 containing a pressure-regulating valve 64 supply compressed air to a primary pressure tank 65 from which compressed air or other gas is supplied through the pipe 66 to the port 67 at the lower end of a primary cylinder 68 containing a piston head 69 reciprocable therein and having a piston rod 70 connected at its upper end to a cross head 71. This in turn is connected through a rod 72 to the load 73 to be raised and lowered. The pressure in the primary pressure tank 65 as supplied to the cylinder 68 is at a degree which is barely insufficient to sustain the load 73 and its connected parts. This deficiency in load-sustaining force is made up by the pressure in the secondary cylinder 74 containing a piston head 75 connected by a piston rod 76 to the cross head 71. Pressure analogous to the overbalancing pressure supplied to the upper side of the piston head 13 in Figure 1 is supplied beneath the piston 75 of the secondary cylinder 74 through a similar arrangement bearing the same reference numerals, namely the pressure-regulating valve 44 and electromagnetic valve 46 located in the pipes 43, 45, 19 leading to the port 17 in the secondary cylinder 74 corresponding to the upper end of the cylinder 16 in Figure 1.

In the operation of the modified pneumatic hoist shown in Figure 2, the pressure-regulating valve 64 is set for a pressure which is not quite sufficient, when admitted beneath the piston head 69 in the primary cylinder 68, to sustain the weight of the load 73 and its connected parts. As a consequence, the load 73 descends to the desired location when no pressure is standing in the secondary cylinder 74.

To raise the load 73, the operator shifts the electromagnetic valve 46 to admit pressure through the port 17 into the secondary cylinder 74 beneath the secondary piston head 75. This pressure needs to be only the amount sufficient to make up the deficiency of pressure supplied to the primary cylinder 68 from the tank 65. As a consequence, the combined pressures in the primary and secondary cylinders 68 and 74 exerted against the piston heads 69 and 75 are sufficient to overbalance the weight or force of the load 73 and its connected moving parts, so that these are raised to the desired height. When the operator desires to lower the load, he operates the electro-magnetic valve 46 so as to vent the air from beneath the secondary piston head 75 to the atmosphere through the pipes 19 and 47. The pressure in the primary cylinder 68 is therefore no longer sufficient to sustain the load, and the latter therefore descends. The air within the primary cylinder 68, however, is forced downward through the port 67 and pipe 66 back into the primary tank 65 and is consequently not lost but can be used over and over again.

While the words "pneumatic" and "air" have been used throughout the present specification

and claim, it will be obvious that any suitable compressed gas may be used in place of air, hence the specification and claim are to be construed as covering any suitable compressed gas.

What I claim is:

A pneumatic hoist for selectively raising and lowering a predetermined load, said hoist comprising a cylinder structure having load-raising and load-lowering spaces therein, a piston structure having load-raising and load-lowering piston areas reciprocable in said load-raising and load-lowering cylinder spaces respectively, a piston rod structure connecting said piston areas to said load, a compressed gas supply tank, a first conduit connecting said supply tank to said load-lowering cylinder space, a compressed gas load-sustaining tank, a second conduit connecting said load-sustaining tank to said load-raising cylinder space, means pneumatically connected to said supply tank for maintaining the gas therein compressed to a predetermined high pressure, a third conduit interconnecting said tanks, a first pressure reducing valve in said third conduit operative to conduct gas therethrough at a predetermined medium pressure from said supply tank 25 to said load-sustaining tank, a second pressure-

reducing valve in said first conduit operative to conduct gas at a predetermined low pressure from said supply tank to said load-lowering cylinder space, and a control valve disposed in said first conduit between said second reducing valve and said load-lowering cylinder space, said control valve being operable selectively to conduct gas through said first conduit and to discharge gas from said load-lowering cylinder space.
